UNITED STATES PATENT OFFICE.

SIMEON DESMOND PURDY, OF FAIRVILLE, NEW BRUNSWICK, CANADA, ASSIGNOR OF ONE-HALF TO T. S. SIMMS AND COMPANY, LTD., OF FAIRVILLE, NEW BRUNSWICK, CANADA, A CORPORATION OF CANADA.

BRUSH.

1,300,012.

Specification of Letters Patent.

Patented Apr. 8, 1919.

Application filed May 9, 1918. Serial No. 233,556.

To all whom it may concern:

Be it known that I, SIMEON DESMOND PURDY, a citizen of the United States of America, residing at Fairville, St. John 5 county, New Brunswick, Canada, have invented a certain new and useful Improvement in Brushes, of which the following is a specification.

My invention relates to brushes and particularly to shaving brushes, the object of my invention being to provide a shaving brush in which are combined the economies and advantages of a one-piece handle, a bunch of brush bristles having its butt set 10 in rubber, an exterior clamping ring surrounding the brush butt, a central core piece, preferably vulcanized into the butt, and a securing nail or screw piercing this core piece and entering the handle to 15 secure the brush bunch to the handle. Other features of value will also appear from the following description or drawings wherein—

Figure 1 is a side elevation of a brush in which my invention is illustratively embodied;

Fig. 2 is a longitudinal section therethrough;

Fig. 3 is a section on the line 3—3, Fig. 2;

Fig. 4 is a longitudinal section showing 30 the brush bunch detached from the handle; and

Fig. 5 is a longitudinal section through a modified construction.

Referring to the drawings, the brush 35 A comprises a bunch of bristles, the butt ends of which are held by a plain clamping ring 10 and embedded in vulcanized rubber. In the center of the brush butt is a core piece 11 of wood, fiber, rubber, metal, or the 40 like. This core 11 is preferably vulcanized in the butt, although it is possible to mold a hole in the butt on the vulcanization of the latter, and thereafter insert the core 11. The shape of the core may be cylindrical (Fig. 45 5) but is preferably tapered in order to better grip the brush bristles.

The handle B, which is preferably turned from wood, has a plain, unthreaded socket 12 bored in one end to receive the butt of the 50 brush, and is of such depth that the outer margin of the clamping ring 10 lies sufficiently far below the lip of the socket to per-

mit the bristles to expand snugly into contact with said lip. In order to hold the brush in the socket, a "dipped" nail 13 is 55 driven through the bore of the core 11 into the body of the handle A, or a screw, peg or other fastening device inserted for the same purpose.

When a securing screw 14 is used instead of a nail, some means should be provided to prevent the brush from rotating in the socket as the screw is turned down. A construction such as shown in Fig. 5 is suitable for this purpose. A channel 65 15 is cut in the bottom of the socket 12 to receive some cementitious substance 16 such as rosin, pitch or the like. The clamping ring 10 is so placed on the brush butt or is of such greater width that its inner 70 margin projects beyond the butt and enters the channel 15. It becomes embedded in the rosin and prevents the rotation of the brush when the securing screw is turned down.

The construction of the brush described 75 renders it a very economical article of manufacture, while at the same time presenting certain structural advantages not heretofore found in brushes of this type.

The constructions shown and described 80 are merely illustrative of what I claim as my invention and are not to be taken as limitative thereof.

I claim:—

A brush comprising a one-piece handle re- 85 cesses at one end to form a plain butt-receiving socket, a bunch of bristles having a butt-end set in rubber and fitting within said socket, said butt-end being substantially flat and bearing against the bottom of the 90 socket, a central core-piece within said butt, a ring surrounding said butt and between which and said core-piece the butt ends of the bristles are confined, such ring being of less width than the depth of the socket 95 in the handle to permit the bristles to expand into contact with the edge of the socket, together with means piercing said core-piece and engaging the handle to secure the bristle bunch thereto.

In testimony whereof I have signed my name to this specification.

SIMEON DESMOND PURDY.
